DOCTOR FOR PAPER MAKING AND LIKE MACHINES

Frederick William Vickery, London, England

Application January 18, 1936, Serial No. 59,718
In Great Britain January 16, 1935

8 Claims. (Cl. 92—74)

In modern doctors a flexible blade is held, but not clamped, at its rear edge in a rigid holder, so that the blade is free to conform closely to the surface of the roll on which it is pressed. There has been a possibility in the past of the doctor being wrongly adjusted to exert too great a pressure on the blade, which has sometimes sprung out of the holder under the excess pressure. To obviate this I have proposed in my 10 U. S. Patent No. 1,912,605 to equip the blade with enlargements or projections standing out from its surface, and to receive these in an undercut slot in the holder so that the blade can be freed from the holder only by longitudinal movement. 15 The term "blade" as used herein includes any such enlargements or projections whether integral or not; and as the enlargements are commonly separate the term lamina is used herein to distinguish the flexible resilient part of the 20 blade to which the enlargements are attached. The present invention aims at the same purpose of preventing the blade from being dislodged under even an excessive working pressure, and achieves it by making a part of the holder movable from the end, the blade, that is to say the lamina, or its projections, or the lamina and its 25 projections being normally engaged by the holder so that lateral withdrawal is impossible and being freed by an operator beside the machine releasing and shifting the movable part.

The movable part of the holder may engage with openings in the lamina, but preferably the lamina is formed or fitted with projections outstanding from its surface as described in my 30 former specification above mentioned, and, as also there described, these either alone or with the rear edge of the lamina are received in what is in effect an undercut or irregular dovetail slot in the rigid holder.

Such a slot may be formed by the putting together of two parts of which the holder is built, and the blade may be freed by simply separating the two parts to a sufficient extent, the holder being so constructed that the requisite separation may be effected from one end of the holder without dismantling it, or one of two parts of which the slot is formed may be notched to allow the passage of the projections of the blade, and moved longitudinally to bring its notches into register with the projections when the blade is to be freed. Or one wall of a slotted holder may be notched opposite the blade projections and a retaining slide may be provided in the holder which also engages the projections and must be

moved lengthwise from its normal position to free them. Instead of a slide moving lengthwise a notched rod may be used and be rotated to bring its notches into register with the blade projections.

These and other embodiments of the invention are described in detail hereinafter, typical constructions being illustrated in the accompanying drawings.

Figure 1 is a cross section on the line I—I of Figure 2, and

Figure 2 a part elevation of one construction;

Figures 3 and 4 are cross-sections of another construction on the line III—III of Figure 5 showing the blade held and freed respectively, and

Figure 5 is a sectional elevation of this construction on the line V—V of Figure 3;

Figure 6 is a cross-section on the line VI—VI of Figure 7, and

Figure 7 an elevation of a third construction;

Figure 8 is a cross section, and

Figure 9 a part view of the locking slide of a fourth construction;

Figures 10 to 12 are cross-sections of constructions in which the retaining means is released by rotation.

Figure 13 is a cross-section on the line XIII—XIII of Figure 14, and

Figure 14 an elevation of yet another construction.

In Figures 1 and 2 the undercut slot in which the rear edge of the lamina 1 and its projections 2 are received is formed by the two parts 3, 4 of which the rigid holder is built. The part 3 has a dovetail sliding connection with the part 4 as indicated, and is prevented from sliding while the doctor is in use by a split pin 5 inserted through it and the part 4 near one end. The front wall of the part 3 is notched as at 6, the notches corresponding in size and relative spacing with the projections 2. But in the working position of the part 3 in which it is held by the split pin, and in which it is shown in Figure 2, the notches 6 are not opposite the projections 2, so that removal of the blade is blocked. When the blade needs to be removed for replacement the split pin 5 is drawn out and the part 3 slid lengthwise until notches and projections register.

In Figures 3, 4 and 5 also the slot to receive the projections of the blade is formed by the putting together of the two parts 7, 8 of which the holder is built; and the blade is released by

simply separating them. For this purpose the part 7 is formed with slanting surfaces 9 on its under side which ride on chamfered pins 10 set in the part 8. When the doctor is working the 5 parts are in the relative position shown in Figures 3 and 5, being pressed together by leaf springs 11. By removing the split pin 5 and pushing the part 7 endwise the machine attendant can lift the part 7 as shown in Figure 4 and the blade can 10 then be removed laterally.

The invention may readily be applied to such forms of holder as are described in my previously-mentioned patent by notching one wall of the retaining slot for the escape of the projections, and 15 inserting in the slot a notched slide. In Figures 6 and 7 the slide 12 is of L-section and in working position blocks the notches 13 in the holder as seen in Figure 7. But it can be freed and shifted until its own notches 14 register with the 20 notches 13 and with the projections 2, and the blade is released.

Or such a slide may be flat as shown at 15 in Figures 8 and 9 and formed with slots 16 opening 25 to the edge of the slide at one end.

Figure 10 shows a form of holder 20 modified to receive and fit a round rod 17 in which are notches 18 extending half across it. As in Figure 7 the front wall of the holder 20 is notched at 30 21 opposite the projections 2 and the notches 18 are normally blocked by the rod 17. By turning the rod through a right angle, its notches 18 are aligned with the notches 21 and the blade is freed.

In Figure 11 the groove to receive the projections 2, which with the groove which receives the rear edge of the lamina constitutes the retaining slot, is formed in the top of a round rod 19, rotatably mounted in the holder 16 in the same way 35 as the rod 17 in Figure 10. When the split pin 5 is removed and the rod 19 turned the rear edge of the lamina is withdrawn from its groove and the blade more or less ejected from the holder. Instead of the rod 19 a tube may be used, similarly 40 mounted and having a slot or perforations (which are to be understood as included by the words slot or slotted in the sub-joined claims) in its upper surface to receive the projections 2.

If the blade, instead of being fitted with 45 projections, is perforated at intervals near its rear edge the moving part of the holder may project retaining pins through its perforations. For example as shown in Figure 12 a rod 22 actuated to turn like the rods 17 and 19 may carry hooks 50 or curved pins 23 which enter openings in the blade on rotation of the rod. Or as shown in Figures 13 and 14 a slide 24 moving endwise may lift retaining pins 25 into the blade perforations. The cam blocks 26 on the slide are preferably 55 made with inverted T-section slots to receive heads on the pins so that they are positively withdrawn on movement of the slide in the opposite direction.

It will be appreciated that in all of the forms 60 described, the blocking means are shiftably carried by the holder and are operable when in one position for blocking removal of the blade and operable in another position for permitting removal of the blade laterally from the holder. 65 The retaining portion of the blade is intended to refer to the projections or apertures in the blade which cooperate with the blocking means.

I claim—

1. A doctor comprising a flexible blade having 70 projections on its surface at intervals along its

length adjacent its rear edge, a holder receiving the rear part of said blade and slotted to receive said projections the outer wall of the slot being notched at intervals to permit passage of said projections, and a slide positioned in said slot of the holder and notched at intervals similarly to the outer wall of the holder, said slide being removable lengthwise of the holder to bring the notches therein into register with the notches in said outer wall to permit passage of said projections through said notches, and movable to cause the imperforate portion of said slide to block the notches in said outer wall and prevent passage of said projections therethrough.

2. A doctor for paper-making and like machines comprising a flexible blade having projections from its surface at intervals along its length adjacent its rear edge, a holder receiving the rear part of said blade, and a round rod supported by and rotatable in said holder and extending 15 to the end of the holder, the forward part of said holder being notched to receive the projections on said blade, said rod having a portion for blocking lateral removal of said projections through said notches when in one angular position.

3. A doctor comprising a flexible blade, a holder provided with a longitudinal groove for receiving the rear edge of the blade, said blade having retaining portions provided with a surface transverse to the side face of said blade adjacent the rear edge thereof, a member extending longitudinally of the holder mounted in a portion of said groove and shiftable relatively to said holder, and blocking means associated with 30 said member, said blocking means being displaceable, upon shifting said member, from a position to engage with the transverse surface of said retaining means and block lateral removal of the blade from said holder to a position out of engagement with said retaining means to permit lateral removal of the blade from the holder.

4. A doctor comprising a flexible blade, a holder for receiving the rear edge of said blade, said blade having a series of projections extending 45 substantially perpendicularly from one side face of the blade and adjacent the rear edge thereof, and a member carried by the holder and shiftable relative thereto, said member extending longitudinally thereof and having portions operable 50 when the shiftable member is in one position for engaging the forward portions of said series of projections to block lateral removal of the blade from the holder.

5. A doctor comprising a flexible blade, projections on the surface of the blade adjacent the rear edge thereof, a holder provided with a longitudinal slot to receive said projections, and a member carried by said holder and shiftable relatively thereto, said member having portions extending in front of said slot to block lateral removal of said projections from said slot when the shiftable member is in one position.

6. A doctor comprising a flexible blade, projections on the surface of the blade adjacent the rear edge thereof, a holder provided with a longitudinal slot to receive said projections, and a blocking member slidably mounted longitudinally of said holder and having a portion in front of said slot, said portion of the blocking member having notches adapted to register with the projections on the blade and being displaceable from a position to permit entry and removal of the projections into and from said slot to a position to

block entry and removal of the projections into and from said slot.

7. A doctor comprising a flexible blade, a holder for receiving the rear edge of said blade, said blade having a series of projections extending substantially perpendicularly from one side face of the blade and adjacent the rear edge thereof, and a member carried by the holder and rotatable relative thereto, said member extending longitudinally thereof and having portions operable when the rotatable member is in one position for engaging the forward portions of said series of projections to block lateral removal of the blade from the holder.

15 8. A doctor comprising a flexible blade, a hold-

er having a longitudinally extending groove for receiving the rear edge of the blade, said blade having a plurality of retaining portions along the length of the blade adjacent the rear edge thereof provided with surfaces transverse to the side face of the blade, a member extending longitudinally of the holder mounted in said groove and shiftable relatively to said holder, and blocking means in said groove displaceable by said shiftable member, said blocking means adapted to engage the transverse surfaces of said plurality of retaining portions, when the shiftable member is in one position, to block lateral removal of the blade.

FREDERICK WILLIAM VICKERY. 15
